SOUND PRODUCING DEVICE

William C. Eaves, Elyria, Ohio, assignor to Eaves Sound Projectors, Inc., New York, N. Y., a corporation of Delaware

Application January 1, 1942, Serial No. 425,368

7 Claims. (Cl. 179—108)

This invention relates to sound producing devices and more particularly to devices of this character which employ a modulated fluid stream as the sound generating medium.

One of the objects of the present invention is to provide novel means for modulating the stream of fluid passing through a fluid flow type sound producing unit whereby sound reproduction of greater fidelity and greater volume can be obtained by said unit than has heretofore been possible in devices of this type operating at like input pressures.

Another object of the invention is to provide novel pressure responsive means for balancing the control valve of a pneumatic sound projecting device.

A further object is to provide novel means for operatively connecting the actuating mechanism of a fluid flow sound producing unit with the vibrating fluid modulating element thereof.

Still another object is to provide a novel sound head for a reproducing unit wherein substantially all resonant frequencies, foreign to the frequency band being reproduced, are eliminated.

A still further object is to provide a novel grid valve for modulating the fluid flow in a sound producing device and novel means for pivotally mounting the movable element of said valve.

A further object is to provide novel adjustable means for applying a balancing force to the vibratory fluid modulating element of a sound head.

Another object is to provide a sound reproducing device having novel means for dampening the natural resonant frequencies of the fluid flow modulating element and for providing a moisture-proof seal between said element and the mechanism for vibrating the same.

A further object is to provide a novel sound reproducing device utilizing a modulated fluid stream to produce the sound wherein differences in the input pressure of the fluid stream have substantially no effect upon the fidelity of the sound reproduction.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference char-

acters refer to like parts throughout the several views,

Fig. 1 is a view in elevation on a reduced scale of one type of sound head embodying the present invention;

Fig. 2 is an enlarged sectional view taken substantially along line 2—2 of Fig. 1 and having parts thereof shown in elevation;

Fig. 3 is a fragmentary sectional view of a portion of the apparatus shown in Fig. 2, the cover of the housing for the actuating mechanism of said apparatus being removed;

Fig. 4 is a fragmentary view in side elevation of the portion of the apparatus shown in Fig. 3;

Fig. 5 is a sectional view, with parts broken away, taken substantially along line 5—5 of Fig. 3;

Fig. 6 is a perspective view of the movable grid of the sound head and the mounting spring therefor;

Fig. 7 is an enlarged view in side elevation of said mounting spring;

Fig. 8 is a sectional view, with parts broken away, of a form of heating unit utilized in the sound head, the section being taken substantially along line 8—8 of Fig. 1;

Fig. 9 is a fragmentary sectional view similar to Fig. 3 of an alternate embodiment of the present invention, with parts thereof shown diagrammatically; and

Fig. 10 is a view similar to Fig. 9 of still another embodiment.

According to the present invention, fluid under pressure is caused to flow through a sound head, and this stream of fluid is modulated by novel control means. The modulated fluid stream constitutes the medium for reproducing and amplifying sounds which have been converted by suitable apparatus into mechanical vibrations and as such have been imparted to the control means.

Referring to the embodiment of the invention illustrated in Figs. 1 to 8, the sound head comprises a housing 26 (Figs. 1 and 2) having a fluid passage 27 extending therethrough and a casing 28 mounted thereon, said casing together with the wall of said housing forming a chamber 29 for containing control apparatus to be more fully described hereafter. Housing 26 is preferably formed in two sections 26a, 26b (Fig. 2) joined by suitable means, such as screws 26c. A source of fluid pressure, as for example, an air compressor unit (not shown) comprising a pump and a reducing valve or other means for maintaining the fluid output of the pump at a substan-

tially constant pressure, is connected to passage 27, preferably by means of a coupling member 30 threaded into the upper end of said passage, the bore of the latter being internally threaded at the end thereof to receive said member. A lock nut 31 may be threaded in the outer end of said bore for engagement with said coupling member in order to securely position the latter. A suitable air filter 32 is held between the inner end of said coupling member and an internal shoulder 33 formed in the wall of passage 27, said filter, as shown, comprising a pair of screen members 34, having disposed therebetween a layer 35 of fibrous material, such as porous felt.

To modulate the stream of air flowing through passage 27, novel valve means of the grid type are interposed in the path of said stream, said means comprising a stationary grid plate 36 (Figs. 2, 3 and 5) and a movable grid plate 37 shown mounted on the low pressure side of said stationary plate for cooperation with the latter. Grid 36 is fixed between sections 26a and 26b of housing 26 to extend transversely across passage 27, and is provided with a plurality of parallel slots or ports 38 (Fig. 5), each of said slots having side walls which are substantially perpendicular to the parallel faces of the plate. Slots 38 are preferably equally spaced across the plate and the solid portions or bars 38a between said slots are of a greater width than the width of said slots, for example, twice the width of the latter.

Grid 37 (Figs. 5 and 6) is also provided with a plurality of parallel slots or ports 39 having bars 39a therebetween, and said slots are of substantially the same length and width as slots 38 and are spaced across said grid in a manner similar to the spacing of slots 38 across grid 36. Grid 37 is mounted so that slots 39 and slots 38 (Fig. 5) are parallel and in staggered relation to each other, each slot of one grid being opposite a bar of the other grid and being preferably located midway between the two adjacent slots of the other grid. In the illustrated embodiment, grid 36 has one more slot than grid 37 whereby the end bars of the latter grid are both disposed opposite slots in the former grid. A greater strength and rigidity may be imparted to grid 37 by increasing the depth of some of bars 39a to form a plurality of longitudinally extending ribs 39b (Fig. 5), on the side of said grid remote from grid 36, said ribs being preferably equally spaced laterally and tapering longitudinally toward the free end of grid 37.

It is desirable that the faces of grid plates 36 and 37 be smooth and that, when valve 36, 37 is in closed or inoperative position, as shown in Fig. 3, the adjoining faces of said valve plates have good surface contact with each other. Accordingly, during fabrication, said plates are preferably honed and lapped to obtain smooth, plane surfaces. Moreover, in order to avoid electrolytic action between the plates and prevent corrosion, the plates are preferably formed from dissimilar metals having a high resistance to corrosion. For example, plate 36 may be formed from brass or German silver while plate 37 is made of Dural or a like aluminum alloy.

The thicker portion of plate 37 extends through a recess 40 (Figs. 2 and 3) in the inner end of section 26b and is mounted in a novel manner in chamber 28 by being formed as one arm of an L-shaped valve member 42, the other arm of said member being numbered 43. Arm 43 is preferably perpendicular to plate 37 and comprises a base portion 43a (Figs. 4 and 6) adjoining said

plate and an elongated lever portion 43b extending outwardly and centrally from said base portion.

Moisture condensed from the air stream in passage 27 if permitted to pass into the chamber 28 tends to corrode or otherwise impair the operation of the control and driving means in said chamber, and to prevent such an occurrence recess 40 has inserted in the wall thereof a member 40a (Figs. 3 and 4) of relatively soft, non-resonant material which engages the thicker portion of grid 37 to close recess 40. Sponge rubber has been determined to be suitable as the material for layer 40a, the latter extending into a dove-tail groove 40b provided in the walls of recess 40. Because of the non-resonant character of the material of pad 40a, the latter also acts to dampen any resonance effects set up in L-shaped member 42, thereby preventing a foreign frequency from being imposed on the voice or other frequencies being produced by the air stream.

To mount valve member 42 for substantially frictionless pivotal movement, a thin, flat member 44 is provided to serve as a torsion spring support therefor. Member 44, which may be formed from spring steel, is secured at the ends thereof by suitable means, such as screws 45, to the wall of housing 26, and intermediate the ends thereof to base 43a, preferably by a pair of rivets 46. As shown, member 44 spans a groove 47 (Fig. 4) provided in the wall of housing 26, said groove extending lengthwise beyond both sides of base 43a. Spring 44 has enlarged end portions 44a for receiving screws 45 and a relatively wide central portion 44b (Fig. 6) for engaging the face of base 43a, said central portion being connected to said end portions by relatively narrow strips 44c. It is preferable that the plane of portion 44b have a slight inclination relative to the plane of portions 44a when spring 44 is subjected to no external forces (Fig. 7) so that when said portions are mounted to become coplanar, as shown in Fig. 3, grid 37 is biased in the direction of grid 36.

To control the pivotal movement of valve member 42 and prevent undue distortion of spring 44, novel bearing means are associated with said member and spring to provide a fixed axis for said pivotal movement. As illustrated, the bearing means comprise a pair of pivot pins 48 (Figs. 3 and 4) embedded in or otherwise rigidly secured to the wall of housing 26 with the outer, pointed ends 48a (Fig. 3) thereof engaging the bottoms of a pair of recesses 49 provided in the ends of rivets 46 (Fig. 6). It is to be understood that recesses 49 are not limited to location in the ends of the rivets but may be disposed at any two points in the face of said spring along the selected pivotal axis and that, if desired, more than two sets of pins and recesses disposed along said axis may be provided to serve as the fulcrum for said spring. Moreover, pins 48 may be mounted for direct engagement with the flat face of spring 44 or rivets 46 may have the heads thereof rounded for direct engagement with the wall of housing 26 so as to dispense with pins 48.

To balance movable valve member 42, a novel control mechanism 50 (Figs. 2 and 3) responsive to the pressures on the high pressure side of valve 37 is provided for applying a torque to member 42 opposite to the torque exerted upon plate 37 of said member by the pressure of the air stream. Mechanism 50 preferably comprises a suitable pressure responsive element, such as

a flat, metal diaphragm 53, mounted across an opening 54 in the wall of housing 26 to communicate with chamber 51, the latter being constituted by the portion of passage 27 between valve 36, 37 and the fluid inlet. Diaphragm 53 is held in fluid-tight engagement with an internal shoulder 55 surrounding opening 54 by an annular member 56, which is secured to housing 26, for example, by screws 57.

A pressure block 52 operatively connects diaphragm 53 to lever 43b, one side of the block engaging the diaphragm substantially across the entire face of the latter and the other side engaging said lever. Preferably, this block is formed of non-resonant, frequency absorbing material, such as rubber, fibre, cork, wood or other similar non-resonant material. Pressure block 52 is thus effective to transmit to lever 43b pressures applied by diaphragm 53 in a direction to oppose movement of said lever to the left as viewed in Fig. 3. The provision of a non-resonant link between diaphragm 53 and lever 43b prevents the transmission of resonance vibrations from said diaphragm to valve member 42, and also acts as an additional pressure compensating element.

The effective area of diaphragm 53 relative to the effective area of grid plate 37, when the latter is in closed position, is such that the torque opposing the pivotal movement in a counter-clockwise direction, as viewed in Figs. 2 and 3, of member 42 and applied by said diaphragm is slightly less than the torque applied by the air under pressure in chamber 51 to plate 37. This pivotal movement of member 42 is opposed not only by the air pressure on the inner face of diaphragm 53 but also by the deformation of spring member 44 and the diaphragm. The resistance provided by spring 44 and diaphragm 53 increases with an increase in the pivotal movement of member 42, while the forces acting on grid 37 due to air flow and air pressure tend to decrease in magnitude as the distance between grid plates 36 and 37 increases. Accordingly, at a point in the angular displacement of member 42, the resisting torque becomes equal to the torque inducing the pivotal displacement and the member is placed in equilibrium or is balanced, whereupon the slightest vibration applied to valve member 42 will produce a responsive vibration of the grid 37.

Novel adjustable means 60 (Figs. 2 and 3) are provided for adding a compensating pressure to diaphragm 53 in order to increase the resistance to counter-clockwise pivotal movement of valve member 42 when such increase is necessary to properly balance said member. As shown, said means comprise a pin 61 slidably mounted in the inner portion 62 of the bore of an externally threaded barrel 63 which extends through a threaded opening in the wall of housing 26. Pin 61, which projects beyond the inner end of the barrel, has a head portion 64 of enlarged diameter which engages an internal shoulder 65 in said barrel. A spring 67 is positioned in the bore of member 63 between the end of portion 64 and a screw member 68, threaded into the outer end of barrel 63. Spring 67 urges the shoulder on pin 61 into engagement with shoulder 65 and the pin into engagement with the inner face of diaphragm 53, the pressure applied by said spring being subject to control by the axial adjustment of screw member 68. The barrel and pin are preferably so located that pin 61 is co-axial with link 52. A lock nut 69 is preferably provided on

barrel 63 to securely hold said barrel in axial adjustment.

When the relationship between the effective areas of diaphragm 53 and grid plate 37 is such that the desired balance of valve member 42 is not attained, the axial position of barrel 63 is adjusted by a suitable tool so that pin 61 will apply the desired pressure to the diaphragm to effect the proper balance. Pin 61, or at least the head thereof, is preferably formed from a relatively rigid, non-resonant material, such as hard rubber, to minimize the possibility of setting up resonant vibrations which are foreign to the sound frequency being reproduced.

15 In order to modulate the air stream flowing through passage 27 and valve 36, 37 and impart desired sound producing characteristics thereto, controlled vibrations within the audible frequency range are transmitted to member 42 and are, in turn, imposed on said air stream by grid plate 37 of said member. For this purpose, suitable actuating means 70 are mounted in chamber 29, for example, by a bracket 70a shown in broken lines (Fig. 2) and, as illustrated, said means 20 comprise an electrical unit of the magnetic type having a U-shaped, permanent magnet 71 carrying a voice coil unit 72, the latter being adapted to respond to current modulations to produce vibrations in an armature 73 corresponding to 25 said modulations. Armature 73 is mounted to have the longitudinal axis thereof substantially parallel to grid 37 and is vibrated by said actuating means in a direction perpendicular to its longitudinal axis. It is to be understood that 30 other types of actuating means capable of imparting controlled vibrations to a movable arm, such as armature 73, may be utilized instead of 35 the magnetic voice coil unit 71, 72.

To faithfully transmit the vibrations from 40 actuating means 70 to grid 37 and thereby attain sound reproduction of high fidelity, a novel connecting linkage is provided between member 42 and said means. As shown, the linkage comprises armature 73 and an element 74 rigidly secured at one end thereof to said armature to extend therefrom at an angle of approximately 45 90° in the direction of member 42, said element being secured at the other end thereof to an arm 75 formed with or otherwise rigidly fixed to arm 43 of the valve member, for example, by 50 being threaded therein. A pair of nuts 76 are in threaded engagement with the externally threaded portion 75a of arm 75, and link 74 is 55 preferably secured to said arm by having the end thereof clamped between said nuts. Arm 75 is mounted so that the extension of the longitudinal axis thereof passes through the center of mass of member 42 and intersects the pivotal axis of said member as determined by bearings 48, 49. It is preferable to mount arm 75 perpendicular to lever 43 and, accordingly, the pivotal axis of 60 member 42 is located in a plane which is parallel to movable grid 37 and which contains the center of mass of said member. As a result of this 65 mounting of arm 75 and member 42, a balanced condition may be more readily imparted to said member and the probability of setting up interfering resonant vibrations in the parts of said member during operation is greatly minimized. 70 The modulated air flowing from valve 36, 37 passes through throat portion 77 of passage 27 to a suitable sound propagating device, such as a horn (not shown), which may be mounted on the externally threaded lower end of section 26b (Fig. 2). However, as the entire volume of air 75

flowing through stationary grid 36 cannot be subjected to the modulating effects of movable grid 37, some air flowing past the edges of the latter as straight jets, a throat 77 is formed to offer a maximum amount of influence on these unmodulated straight jets and, in the illustrated embodiment, said throat is constricted in somewhat the same manner as the throat portion of a Venturi tube, being proportioned to dissipate the energy of the currents of unmodulated air and thereby preventing said currents from flowing to the horn as straight jets with ensuing hissing noises.

The formation of ice on the surfaces of grids 36 and 37 or on the walls of the portions of passage 27 adjacent said grids seriously affects the quality of the sound reproduction and may render the sound head inoperative. Accordingly, suitable means for preventing the formation of ice on the walls of passage 27 and on the surfaces of plates 38 and 37 are provided, and in one form comprise a substantially cylindrical container 79 (Figs. 1 and 8) formed with housing 26 in the lower end of section 26a of said housing, said container having an open end and a flange 80 formed at said end. An electrical heating assembly 81 is positioned in container 79 through the open end of the latter, and is connected by suitable means, such as a cable 82, to a source of electrical energy (not shown), said cable having an annular, transversely disposed disc 83 secured thereon and adapted to be fixed to flange 80 by means of screws 84. Heat generated in heating assembly 81 is conducted to valve 36, 37 and the adjacent walls of passage 27 to maintain the parts at a temperature exceeding the freezing temperature of water. Other heating arrangements may also be utilized for the purpose of preventing ice formation; for example, a heating assembly may be located on the interior of housing 26 in chamber 51, or a heating element may be mounted in contact with stationary grid 36 adjacent the walls of passage 27.

During the operation of the above-described air head, it is desirable that the pressure of the fluid admitted to passage 27 be maintained at a constant value. The pressures available for operation of the unit range from pressures sufficient only to produce an air stream through the air head, e. g., pressures less than 3 lbs. per sq. in. gauge, to pressures limited only by the structural resistance of the parts of the unit directing and controlling the air stream. The fidelity of sound reproduction obtained by the sound head is substantially unaffected for an operating pressure selected from the range of pressures between 3 lbs. per sq. in. gauge and 45 lbs. per sq. in. gauge, the higher operating pressure having the effect of producing a greater volume of sound. Chamber 51 on the high pressure side of valve 36, 37 is of sufficient cross-sectional area and volume to exceed the flow capacity of said valve at any given pressure of entering fluid. Accordingly, said chamber acts as a reservoir for the fluid stream and maintains the air pressure adjacent the high pressure side of valve 36, 37 substantially constant while a continuous stream of air flows through said valve. Grid 37 is balanced in the air stream by pressure responsive means 50, compensating means 60 and spring 44, and is vibrated by actuating means 70 to impart sound producing modulations to said stream.

Another embodiment of the invention, including an alternate mounting arrangement for the movable grid of the control valve and a novel

connection to said member from the actuating means, is shown in Fig. 9. The flow of fluid through passage 27 is modulated by a valve comprising stationary grid 36 and a movable grid 85 cooperating with the stationary grid to perform the same function as plate 37 of Figs. 1 to 8. However, grid 85 is disposed on the high pressure side of grid 36 rather than on the low pressure side, as in the first embodiment, and extends through a recess 86 in the lower end of housing section 26a, said recess being suitably lined with a layer 87 of relatively soft, non-resonant material, such as sponge rubber. If desired, grid 85 may be pivoted at the left hand end thereof to housing section 26a, or said grid may be "floated" in operative position merely by its connection to armature 93 to be described hereafter, but preferably said grid 85 forms one arm of a valve member 88, which is pivotally mounted on the exterior of passage 27 by a torsion spring 89 similar to spring 44, spring 89 being initially deformed, however, to apply a counter-clockwise torque (as viewed in Fig. 9) to member 88.

Pressure responsive unit 50 is connected by non-resonant link 52 to the upper end of an arm 90 formed with member 88 so as to apply a clockwise torque to the latter when actuated by pressures in chamber 51. The effective pressure area of the diaphragm of said unit relative to the area of grid 85 is such that the admission of air, or other fluid, under pressure to chamber 51 causes said unit to apply a sufficiently greater torque to member 88 than is applied thereto by the pressure of the air on grid 85 to pivot said member clockwise and move grid 85 away from stationary grid 36. The differential torque producing this pivotal movement decreases as the magnitude of the movement from initial closed position increases because of the resistance to deformation offered by such members as the diaphragm of pressure unit 50 and spring 89 and, accordingly, an equilibrium condition is achieved at a suitable point in the displacement of said member. It is to be understood that suitable means, such as compensating means 60 (Fig. 3), for applying an additional force tending to balance member 88 may be provided in the unit of Fig. 9 if proper balance cannot be otherwise attained, as for example at a low operating pressure.

To impart vibrations to member 88 and thereby modulate the air stream in passage 27, electromagnetic actuating means 91 are provided, and are shown diagrammatically in Fig. 9 as comprising a magnet 92 and a voice coil 92a. To transmit vibrations to valve member 88 in accordance with modulations in the current passing through coil 92, an element 93 is integrally formed with or rigidly secured to said valve member 88 and is mounted to be substantially parallel to grid 85 and to extend in the direction of actuating means 91. The free end of said element is located in the magnetic field of said actuating means to serve as the armature thereof and, accordingly, provides for the direct transmission of vibrations from said actuating means to the movable valve member.

Still another embodiment of the present invention is shown in Fig. 10 and comprises a housing 94 having a fluid passage 95 formed therein. Valve means corresponding in structure to valve means 36, 42 of the embodiment of Figs. 1 to 8 are provided for modulating a fluid stream flowing through said passage, and comprise a sta-

tionary grid 97 and a movable member 98 having grid 99 formed therewith. Valve member 98 is pivoted on a torsion spring 100 mounted and constructed like spring 44 and is operatively connected to a pressure responsive unit 101 similar in structure and operation to unit 50, the unit 101 being adapted to apply a balancing torque to said valve member.

In order to actuate movable grid 99 and impart controlled vibrations to the latter, a lever or arm 102 is formed with or otherwise rigidly secured to said plate at the end thereof remote from the pivotal axis, said lever extending through a recess 103 in housing 94. A layer 104 of non-resonant material, such as sponge rubber, may be provided in a groove in the walls of said recess to engage and form a substantially fluid-tight seal with the side and bottom faces of said lever. The free end of lever 102 is actuated by suitable electromagnetic means comprising a magnet 106 and a voice coil 107, said lever constituting the armature of said means. This novel arrangement provides a direct connection between the actuating means and the vibrating valve member so that the vibrations are transmitted to the latter through a minimum mass of material whereby sound reproduction of a greater fidelity and superior tonal qualities may be obtained by the unit embodying this structure.

There is thus provided a novel sound reproducing unit of the fluid flow type, i. e., of the type utilizing a modulated fluid stream, preferably an air stream, as the sound generating medium. The novel sound head comprises valve means for modulating a fluid current, and novel means responsive to the pressure of the fluid current for applying a balancing torque to the movable member of said valve means. A novel vibration transmitting linkage operatively connects the movable member of the valve with the actuating means, and novel means are provided for preventing the formation of ice in or on said unit where such formation would cause improper operation of said unit and for preventing moisture, which condenses from the fluid stream, from flowing to the control and actuating apparatus mounted exteriorly of the fluid flow passage. Other novel means embodied in the present invention are operative to prevent the creation of resonant vibrations in the parts of the unit connected to the control member and to thus maintain a high fidelity of sound reproduction. The movable member of the grid type, fluid modulating valve is mounted in a novel manner so as to be readily pivoted by the fluid stream to an equilibrium position, in which position said member is extremely sensitive to vibrations imparted thereto by the actuating means.

Although several embodiments of the invention have been illustrated and described, it is to be expressly understood that the same is not limited thereto. The flat diaphragm, which constitutes the pressure responsive element of the balancing means, may be replaced by other elements or means responsive to pressure differentials existing between opposite sides or faces thereof. Various other changes may be made in the design and arrangement of parts without departing from the spirit and scope of the invention. For a definition of the invention, reference will be had primarily to the appended claims.

What is claimed is:

1. In a sound reproducing unit utilizing an air stream as the sound generating medium, the com-

bination with control means for modulating the air stream including valve means of the grid type having a movable member in the path of said air stream, of means actuated by the pressure of said air stream for applying a balancing force to said movable member opposed to the force exerted thereon by the fluid stream, and spring-pressed means for augmenting the balancing force applied by said pressure actuated means, said spring-pressed means and said pressure actuated means being so arranged and proportioned relative to said member as to balance the latter in open position in said stream.

2. In a sound head of the fluid flow type having valve means for imparting modulations to a fluid stream, the combination therewith of means for balancing said valve means in open position in said fluid stream, said balancing means comprising a mechanism actuated by the pressure of the fluid stream for engaging and applying a balancing force to said valve means, and a spring-pressed, non-resonant member adapted to engage said mechanism during the movement of said valve means to open position to augment the balancing force applied by said mechanism.

3. In a sound head adapted to reproduce sounds by means of a modulated fluid stream, valve means in the path of said fluid stream for modulating the latter, means for balancing said valve means in open position in said fluid stream to render said valve means accurately responsive to actuating vibrations, and means connecting said balancing means to said valve means, said connecting means comprising a link of non-resonant material adapted to prevent the transmission of resonant vibrations between said balancing and said valve means.

4. In a sound head adapted to reproduce sounds by means of a modulated fluid stream, valve means in the path of said stream, for modulating the latter, and means for balancing said valve means in open position in said fluid stream to render said valve means accurately responsive to actuating vibrations, said balancing means comprising a mechanism disposed substantially parallel to the fluid stream and actuated by the pressure of the fluid stream for engaging and applying a balancing force to said valve means and a spring-pressed non-resonant member adapted to engage said mechanism during the movement of said valve means to open position to augment the balancing force applied by said mechanism.

5. In apparatus of the class described, means comprising a fluid passage, valve means for controlling a fluid stream produced by the admission into said passage of a fluid under pressure, said valve means comprising a stationary grid and a movable grid mounted on the low pressure side of said stationary grid, a member rigidly secured to said movable grid, means for pivotally mounting said member on the exterior of said passage, said last-named means comprising a torsion spring secured to said member, said spring urging said movable grid toward closed position, balancing means including an element responsive to the difference between the pressures on the interior and exterior of said passage, and a link of non-resonant material operatively connecting said pressure responsive element to said member, said balancing means and said spring applying torques to said member balancing said grid in the fluid stream.

6. In sound reproducing apparatus of the type

having a movable grid member for modulating a fluid stream in response to the movement of a vibrating armature, a resilient element attached to said member and having a central portion inclined relative to the plane of the end portions thereof to serve as a torsion spring mount therefor, bearing means constituting a fulcrum for said element, and means for operatively connecting said armature to said member to operate the latter, said connecting means comprising an arm rigidly secured to said member and substantially parallel to said armature, said arm having the axis thereof disposed in a common plane with the pivotal axis of said member and passing through the center of mass of said member.

7. In a sound reproducing unit of the type

having a movable valve member for modulating a fluid stream in accordance with the movement of a vibrating armature, means for pivotally mounting said member for angular movement about a fixed axis, and means for operatively connecting said armature to said member to actuate the latter, said connecting means comprising a link rigidly secured to said member, and means for transmitting the vibration of said armature to said link in a direction perpendicular to the longitudinal axis of said link, the latter being mounted to have the longitudinal axis thereof pass through the center of mass of said member at an angle of 90° to the pivotal axis of the latter.

WILLIAM C. EAVES.
